WRITING INSTRUMENT

Gino Di Spirito, Hasbrouck Heights, N.J., assignor to
All-Rite Pen Company, Inc., Hackensack, N.J., a cor-
poration of Delaware

Filed Dec. 29, 1967, Ser. No. 9,978

Term of patent 14 years

Int. Cl. D19—06

U.S. Cl. D74—17

FIG. 1 FIG. 2 FIG. 3

FIG. 4

FIG. 5

FIG. 1 is a front elevational view of a writing instrument showing my new design;

FIG. 2 is a side elevational view thereof;

FIG. 3 is a rear elevational view;

FIG. 4 is a top plan view of the writing instrument, and

FIG. 5 is a bottom plan view thereof.

I claim:

The ornamental design for a writing instrument, substantially as shown.
